Primary Examiner — Elizabeth Albert*Assistant Examiner* — Kelley Donnelly(74) *Attorney, Agent, or Firm* — Lerner, David, Littenberg, Krumholz & Mentlik, LLP**(57) CLAIM**

The ornamental design for audio video shelving unit, as shown and described.

DESCRIPTION

FIG. 1 is a front perspective view of the subject audio video shelving unit;

FIG. 2 is a front view thereof;

FIG. 3 is a rear view thereof;

FIG. 4 is a right side view thereof (the left side view is a mirror image of the right side view); and,

FIG. 5 is a top plan view thereof.

The broken lines showing in FIGS. 2 and 3 are included for the purpose of illustrating environment and form no part of the claimed design.
